(57) **CLAIM**

I claim the ornamental design for a handlebar, as shown and described.

DESCRIPTION

FIG. 1 is a perspective view of a handlebar, showing my new design;

FIG. 2 is a front elevational view thereof, illustrated as in use on a vehicle;

FIG. 3 is a front elevational view thereof;

FIG. 4 is a rear elevational view thereof;

FIG. 5 is a right-side elevational view thereof, the left-side elevational view being a mirror image thereof;

FIG. 6 is a bottom plan view thereof; and,

FIG. 7 is a top plan view thereof.

The broken lines showing a motorcycle in FIG. 2 and handlebar attachments in FIG. 7 are included for the purpose of illustrating the invention in use, and form no part of the claimed design.
